Harry Lamb, Birmingham, England, assignor to Standard Cameras Limited, Birmingham, England, a company of Great Britain

Application May 7, 1951, Serial No. 15,090
In Great Britain December 8, 1950

Term of patent 14 years

(Cl. D61—1)

To all whom it may concern:

Be it known that I, Harry Lamb, subject of the King of Great Britain and Ireland, residing at Birmingham, England, have invented a new, original, and ornamental Design for a Camera or
the like, of which the following is a specification,
reference being had to the accompanying drawing,
forming part thereof.

Fig. 1 is a front and top perspective view of a camera or the like, showing my new design; and

Fig. 2 is a bottom and rear perspective view thereof.

I claim:

The ornamental design for a camera or the like,
substantially as shown.

HARRY LAMB.
